COIL FORM

William F. Stahl, 423 Abbotts Fork Road, Kenilworth, Ill.
Filed June 4, 1962, Ser. No. 199,684
2 Claims. (Cl. 242—118.7)

This invention relates to a coil form, and, more particularly, to a separable frame upon which electrical wiring is wound so as to serve as an inductor.

The device with which the invention is concerned is 10 variously termed "bobbin" or "spool," and is characterized by a tubular body equipped with end flanges, see, for example, applicant's prior Patent No. 2,375,704.

It is a general object of this invention to provide a novel coil form and, more particularly, a coil form made up 15 of identical halves which are advantageously produced by molding of plastic materials.

Another object of this invention is to provide a two-piece coil form made up of halves uniteable along a longitudinal line of separation and which is characterized by 20 advantageous dimensional stability.

Still another object of the invention is to provide a novel lockable joint between the two longitudinal halves of a coil form or bobbin. Other objects and advantages may be seen in the details of construction and operation set 25 down in this specification.

This invention will be explained in conjunction with an illustrative embodiment in the accompanying drawing, in which—

FIG. 1 is a perspective view of the assembled form of 30 the invention;

FIG. 2 is a perspective view of one identical half of the form seen in FIG. 1;

FIG. 3 is a plan view of the FIG. 1 assembly;

FIG. 4 is a side elevational view of the assembled form 35 seen in FIG. 3;

FIG. 5 is a sectional view, taken along the sight line 5—5 of FIG. 4; and

FIG. 6 is a fragmentary sectional view, in enlarged 40 scale, such as would be seen along the sight line 6—6 of FIG. 3.

Referring to the drawing, the numeral 10 designates generally the inventive coil form, which is seen to be made up of two longitudinal halves 11 and 11'. The halves 11 and 11' are identical, and each includes a tubular body or spool portion 12 and 12' equipped with integral end flanges 13, 13' and 14, 14'. The body portions 12 and 12' are seen to be U-shaped in transverse section so that when the two parts 11 and 11' are joined together, a rectangular cross section is evolved. In similar fashion, the flanges 13, 13' and 14, 14' are generally rectangular, and when united as seen in FIG. 1 define rectangular end flanges. It will be immediately apparent that in some installations the cross-sectional configuration of both the assembled spool portions 12, 12' and the flanges 13, 13' and 14, 14' may be square rather than rectangular.

Each flange 13, 13' and 14, 14' is equipped with corner openings 13a and 14a for mounting and for receipt of the wire connectors to the conduits (not shown) wound on the assembled spool parts 12, 12' between the assembled flanges 13, 13' and 14, 14'.

As best seen in FIG. 2, each half 11 is equipped with shoulders S and T which define reduced thickness areas 15 and 16 on one side of the flanges 14 and 13 and re-

2

duced thickness portions 17 and 18 on the other side of the two flanges, i.e., the side associated with the shoulder T. The shoulder S develops a reduced thickness portion 19 in the body 12, while the shoulder T develops a reduced thickness section or area 20 in the body 12. Each of the reduced thickness areas in the flanges 13 and 14, i.e., the portions 15—18, 15'—18', are equipped with a detent 21.

It will be seen that the shoulder S is on the inside or confronting faces of the flanges 13 and 14, while the shoulder T is on the outside of these two flanges. The shoulder S is continuous, as is the shoulder T, so that the areas 17, 20 and 18 effectively define what might be considered a male fitting or joint portion, while the areas 15, 19 and 16 define a female fitting. Thus, each part 11, 11' is hermaphroditic. Both the male and female fittings are seen to be U-shaped when viewed from the side, and mate with cooperative fitting portions on the complementary half. However, each half is identical, so that the coil forms can be mass-produced by conventional molding methods. The detents 21 are mutually engageable to provide a rigid coupling so that the coil forms can be mass mounted on a mandrel for simultaneous winding with the assembled spool parts 12, 12' being dimensionally stable. For example, the detent 21 on the portion 16 of one half 11 mates with the detent 21 provided on the portion 18' of the other half 11 (see FIG. 6).

As a specific example of the invention, the form 10 was constructed of fairly rigid polyethylene having a thickness of about 0.050". The reduced thickness portions 15—20 were all about 0.025" in thickness. Thus, there was sufficient "give" or resilience to permit the detents 21 to mutually engage. In the illustration given, the assembled flanges 13 measured 2" x 1 1/2", and the assembled body 12 1" x 5/8". The shoulders S and T were spaced 3/32" back from the edge at the open side of the body 12. Preferably, the reduced thickness portions 15—20 are about one-half the thickness of the other portions of form 10, of the order of 0.015—0.030" as compared to 0.030—0.060".

While, in the foregoing specification, a detailed description of an embodiment of the invention has been set down for the purpose of illustration thereof, many variations in the details herein given may be made by those skilled in the art without departing from the spirit and scope of the invention.

I claim:

1. A coil form, comprising a pair of mating parts, with each part including an essentially rigid plastic body having three connected sides providing a U shape in transverse section and defining an open mating side, said body at each end being equipped with an integral transverse flange extending peripherally outwardly from each side to provide parallel flanges having inside surfaces in confronting relation, said body and flanges adjacent said open side being equipped with a pair of perimetric shoulders adjacent to said open side to provide reduced thickness portions, each shoulder commencing at the periphery of one of said flanges and continuing to the periphery of the other flange, one shoulder including an intermediate portion extending along the outside of said body and

- end portions extending along the inside surfaces of said flanges, the other shoulder including an intermediate portion extending along the inside of said body and end portions extending along the outside surfaces of said flanges whereby identical mating shoulders are provided in said parts, and
- a detent in each reduced thickness portion of each flange for maintaining said parts in connected relation, each detent including a generally circular depression extending toward the other flange.
2. The structure of claim 1 in which said form is constructed of polyethylene having a thickness of the order of 0.030-0.060", with the reduced thickness portions being

5

10

of the order of one-half the thickness of the remainder of the form.
